ELECTRIC SWITCH

Carl A. Schaefer, Detroit, Mich., assignor to
 Square D Company, Detroit, Mich., a corpora-
 tion of Michigan

Application November 21, 1936, Serial No. 112,088

7 Claims. (Cl. 200—50)

This invention relates to interconnected electric switch combinations and more particularly to an electric switch combination of manually and automatically operable switches providing for simultaneous switch operation under certain conditions.

In the use of automatic electric switches responsive to external conditions it often becomes desirable to maintain the switch in a definite position irrespective of the external condition in conjunction with the operation of associated devices. One specific example of this is in the control of ice cream cabinet motors wherein a hardening cabinet and a freezer are provided with the same compressor supplying the refrigerant for the freezer and the cabinet. The pressure switch is here normally responsive to the temperature of the hardening cabinet and it is desirable that when freezing the pressure switch be maintained in its closed position so that the compressor motor will operate regardless of the cabinet temperature. This operation is in conjunction with the operation of a freezer motor which stirs the batch to be frozen.

One application of applicant's invention is a switch combination wherein the starter switch for the freezer stirring motor is mechanically coupled with the automatic pressure switch responsive to the hardening cabinet temperature so that operation of the starter switch to initiate operation of the freezer motor will insure the closing or maintaining closed of the pressure switch contacts while the freezer motor is in operation regardless of the hardening cabinet temperature. It is, of course, to be understood that this is only one of the many applications to which applicant's invention is readily adaptable.

One object of the invention is the combination of an electric switch controlling a translating device with a switch automatically operable in response to an external condition controlling a second translating device, having provision for insuring maintaining of the automatic switch in a definite operating position irrespective of the condition upon actuation of the first switch to an operating position.

Another object of the invention is the combination of a manually operable switch and a switch automatically operable in response to an external condition, having provision for insuring the closing of the automatic switch irrespective of the condition when the manual switch is closed.

Other objects and features will be readily apparent to those skilled in the art from the following specification and the appended drawing

illustrating certain preferred embodiments of the invention in which:

Figure 1 is a front elevational view of the switch combination according to the present invention with the cover removed and certain parts broken away to show internal parts.

Figure 2 is a partial vertical sectional view on the line II—II of Figure 1.

The switch combination according to the present invention comprises an outer enclosing box 10, provided with a removable cover, not shown, within which are mounted a motor starting switch designated generally at 2 and a pressure switch at 3. The motor starting switch corresponds to that shown in the patent to H. L. Van Valkenburg, et al., 1,912,109, granted May 30, 1933, and comprises an insulating base 4 having mounted thereon a plurality of stationary contact elements 5. Guided for rectilinear movement at right angles to the base is an insulating yoke 6 carrying movable bridging contact elements 7. The switch is provided with a pair of push buttons 8 and 9 for manually opening and closing the contacts and with overload relays indicated generally at 11 and 12 for automatically opening the contacts in response to an overload through the switch, all as more fully described and claimed in the aforesaid patent.

The pressure switch according to the present invention follows substantially the form described in applicant's co-pending applications 77,723, filed May 4, 1936, for Electric switches and 101,367, filed September 18, 1936, for Electric switches and comprises a pair of contact arms 13 and 14 with the arm 13 formed of magnetic material and having a limited relative movement with respect to the arm 14 which carries the movable contact 15. A permanent magnet 16 cooperates with the magnetic arm 13 to effect a quick make and break of the contacts as more fully described in the aforesaid applications. A stationary contact 17 is movably mounted to vary the differential of operation of the switch. The arm 13 adjacent its lower portion is provided with a pin 18 adapted to be engaged by an insulating portion 19 rigid with a metallic lever 21 hinged to a fixed part. The arm 14 is biased toward contacts engaged position by a spring 22 and is moved to disengaged position by engagement of the portion 19 with the pin 18. For moving the lever 21 there is provided a bellows chamber 23 having a bellows 24 therein to which is connected a pin 25 bearing against the under part of the lever 21. Bearing against the upper surface of the lever 21 is provided a compression

spring 26 engaged at its upper end by a nut 27 threaded upon an adjusting screw 28 to provide adjustment of the range of operation of the switch. Guided for vertical reciprocating movement by means of openings in the top and bottom of the pressure switch cover is a rod 29 biased in a downward direction by springs 31 and carrying a projection 32 engageable with the under side of the lever 21 to move it to its upward position. The exterior end of the rod 29 is pivotally mounted to an operator 33 which, when moved downwardly, is adapted to pivot about the point 34 to move the rod 29 upwardly and through the projection 32 the lever 21 also. For moving the operator 33 there is provided a U-shaped bracket 35 rigidly mounted on the side walls of the outer enclosing box and within this bracket is guided a sliding member 36 biased in an upward direction by a spring 37. The lower end of the sliding member 36 is disposed to engage the operator 33 when the member is moved downwardly. Pivotally mounted on the side wall of the box is a bell crank lever 38 having an extension 39 on one leg in the path of and adapted to be moved by a projection 41 on the insulating yoke 6 of the motor starting switch. The other leg of lever 38 is adapted to engage with and depress the member 36.

The operation of the device should be readily apparent from the above description. When the motor starter switch 2 is operated by pressing on the start push button 3 the yoke 6 will be moved downwardly and the projection 41 will engage the extension 39 on the bell crank lever 38 and will rotate the bell crank in a clockwise direction as viewed in Figure 2. This will move the sliding member 36 in a downward direction and will thus depress the corresponding end of the operator 33 thus raising the rod 29 and through the projection 32 the lever 21 also, unless it was already in the upward position. This arrangement insures that the pressure switch contacts will always be in a desired operating position, which as here illustrated is closed, while the starting switch is in its closed position.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What is claimed is:

1. In a device of the class described, a pair of electrically independent electric switches, one of said switches being automatically operable in response to an external condition, the other of said switches being manually operable at will, and a mechanical connection between said switches whereby manual operation of said last mentioned switch to one operating position effects operation of said first mentioned switch to a definite operating position irrespective of said external condition.

2. In a device of the class described, a set of cooperating contacts automatically operable to open and closed positions in response to an external condition, a second set of cooperating contacts manually operable to open and closed positions at will, and means for closing said first set of contacts irrespective of the condition when said second set of contacts is manually operated to closed position.

3. In a device of the class described, a motor

starting switch, an electric switch automatically operable in response to an external condition and means operating in response to closing of the motor starting switch for holding the automatic switch closed irrespective of the nature of the external condition, said means positively moving the automatic switch to closed position if it should be open in response to the external condition when the motor starting switch is closed.

4. In a device of the class described, a manually operable electric switch for controlling an electric translating device, an electric switch automatically operable in response to an external condition for controlling a second electric translating device, and mechanical connection between said switches for holding the automatic switch closed irrespective of the nature of the external condition when the manual switch is closed, said connection effecting the movement of the automatic switch to closed position if it should be open in response to the external condition when the manually operable switch is closed.

5. In a device of the class described, an electric switch automatically operable in response to an external condition, including a switching lever, a member engageable with said lever to maintain it in contacts engaged position, a second electric switch, and mechanism movable by the closing of said second electric switch for moving said member to maintain closure of said automatic switch irrespective of the condition while said second electric switch is in closed position, said member and mechanism effecting the movement of said lever to the contacts engaged position of the automatic switch if it should be in contacts disengaged position in response to the external condition when the second electric switch is closed.

6. In a device of the class described, an electric switch for controlling a translating device, an electric switch automatically operable in response to an external condition for controlling a second translating device and including a switching lever, a member engageable with said lever to maintain it in contacts engaged position, an operator connected to said member and adapted to move it to lever engaging position when depressed, a member slidably mounted to engage said operator, a bell crank lever engaging said last mentioned member, and a part on said first mentioned electric switch engageable with said bell crank lever when moved to contacts engaged position to effect movement of said parts and the maintaining of said automatic switch contacts in closed position irrespective of the external condition.

7. In a device of the class described, an outer enclosing box, a manual motor starting switch mounted in said box for controlling a translating device, an electric switch mounted in said box and automatically operable in response to an external condition for controlling a second translating device, a bell crank lever pivotally mounted on said box and having a part engageable by said manually operable switch, a reciprocable member mounted on the box and having a part engageable by said bell crank lever, and mechanism on said automatically operable switch and including a part engageable by said member for maintaining the automatic switch in closed position irrespective of the external condition upon closing of the manual switch.
